DISPLAY DEVICE

Richard Eaton Paige, Flushing, N. Y.

Application February 25, 1933, Serial No. 658,507

4 Claims. (CL. 206—44)

This invention relates to new and useful improvements in methods of manipulating flexible materials such as paper, cardboard and relatively light thin metals.

5 It is an object of the invention to provide a new and novel method of scoring, creasing and bending such materials, preferably cardboard, whereby novel and attractive effects, especially in advertising and similar display devices, may be obtained.

A feature of the invention resides in the scoring of flexible materials on curved or angularly disposed lines in such a manner that the material may be flexed as by circumflexion or circumflexion about centers which may be located within the confines of the material operated upon or at points removed therefrom.

A further feature of the invention resides in a novel method which will permit of causing a flat piece of material having but two dimensions, length and width, excluding of course its thickness, to assume a third dimension, depth.

In carrying out the present invention, a piece of material of two dimensions as above described is scored as desired upon its opposite faces, after which it may be folded upon said scored lines to produce the article described. The folding is produced by circumflexion or circumflexion about centers bearing a definite relation to the scored lines. This folding of the material reduces the area, length and breadth, and throws the surplus material into a third dimension of depth.

It has been found in actual practice, that material manipulated in the afore-mentioned manner is, in the finished article, placed under tension which condition adds materially to the strength thereof and produces inherent strength in the finished product to a degree far beyond that possessed by the material in its original state.

This last mentioned feature of the invention is of particular importance since it permits of production of display devices from relatively light thin material which when finished will be possessed of great strength. Furthermore, the use of light thin material permits of a greater latitude of circumflexion and circumflexion than is possible with stock or material of the heavier weights and greater thicknesses.

Still another feature of the invention resides in the fact that after the material or stock has been conditioned and flexed once into shape to produce the finished article, it will, after being knocked down or collapsed, readily reassume the form which it is finally to take. This is also an important feature of the invention, since it great-

ly simplifies the setting up of the device by persons not thoroughly familiar with such processes.

Certain other features of the invention relate to the peculiar combinations of curved, arcuate and angular scoring and flexing of materials or stock which in themselves are possessed of but little supporting strength and which are, by the present invention, successfully employed in the production of novel and highly attractive display devices capable of supporting greater weights and withstanding greater strains than any similar devices with which I am familiar.

10 Other features of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Figure 1 is a perspective view of a display device in the form of a so-called display basket, constructed in accordance with the present invention.

Figure 2 is a transverse sectional view thereof, taken on an enlarged scale, on the line 2—2 of Figure 1.

Figure 3 is a longitudinal sectional view thereof taken in a plane at right angles to Figure 2.

Figure 4 is a fragmentary rear elevational view,

Figure 5 is a plan view of a blank from which the device illustrated in Figure 1 is formed,

Figure 6 is a fragmentary view in elevation, illustrating a modified form of the invention,

Figure 7 is a plan view of a blank from which the device illustrated in Figure 6 is formed,

Figure 8 is a fragmentary plan view illustrating a still further modified form of the invention,

Figure 9 is a perspective view of a still further modified form of the invention,

Figure 10 is a vertical sectional view thereof, and

Figure 11 is a plan view illustrating the blank from which the modified form illustrated in Figures 9 and 10 is constructed.

In that form of the invention illustrated in Figures 1 to 5 inclusive, my invention takes the form of a display device particularly adapted for use on counters or tables and adapted to contain

small articles of merchandise, and to display advertising copy relating thereto.

In this form, the invention consists of a main body portion 10, having a bottom 11, a depending flange 12 which defines the upper edge of the main body portion 10, and a wing extension 13, which latter is provided for the purpose of displaying suitable copy relating to the commodity offered for sale, samples of which are to be displayed in the basket-like receptacle formed by the body portion 10.

The device is formed from a single piece of flexible material, preferably cardboard from which a blank such as illustrated in Figure 5 is formed. The blank in Figure 5 is designated A. To produce a device such as illustrated in Figures 1 to 5, the blank A is formed with a straight side edge B and curved end edges C and D. The curved end edge D merges into a straight edge E which terminates at the end of an extended portion F. The blank is cut along the lines 20, 21, 22 and 23 to remove a portion thereof as indicated by the space G in Figure 5. Cutting along the lines 23, 24 and 25 provides an extension H which, when the device is set up for use, occupies an upright position so that copy printed upon the front face thereof will be plainly visible.

In addition to being cut as above described, the blank A is scored in the manner hereinafter described in order that the blank may subsequently be flexed into its final form. One line of scoring designated 30 is slightly spaced from the outer edge of the blank, and extends parallel therewith from the end of the extended portion F, to the point 31 where it joins the inner end of the cut line 25. This scored line 30 is formed upon the upper face of the blank as it is shown in Figure 5, and that area of the blank which lies between the outer edge thereof and the scored line 30, forms the depending flange 12 heretofore mentioned.

The blank A is also scored along the straight lines 32, 33 and 34, these scored lines being formed upon the under face of the blank as it is shown in Figure 5. The scored line 32 is connected with the scored line 33 by a curved or arcuate scored line 35 at one of its ends, its opposite end being connected with the scored line 34, by an arcuate scored line 36. Both of these arcuate scored lines 35 and 36 are formed upon the under face of the blank as it is shown in said Figure 5.

In forming an article as herein illustrated, scored lines such as 37 and 38 are also employed. The scored lines 37 extend radially from the axis 39 of the arcuate scored line 35 and terminate at those points where they intersect this scored line 35, the radially extending scored lines 38 extending from the axis 40 of the arcuate scored line 36 to the points where they intersect said scored line 36. These scored lines 37 and 38 are formed upon the under face of the blank as it is shown in Figure 5. In addition to the scored lines above mentioned, there is a scored line 41 which extends from the axis 40 of the arcuate scored line 36 to the cut edge 23 of the blank. It will also be noted that the cut line 21 extends the full distance between the axis 39 of the arcuate scored line 35 and the axis 40 of the arcuate scored line 36. The scored line 41 herefore mentioned is formed upon the under side of the blank as it is shown in Figure 5 and this scoring, together with the cut line 21, forms an area 44 the purpose of which will be hereinafter explained.

The depending flange 12 is formed with a slit or similar opening 45 near one end, and upon its opposite end, there is a suitably formed tongue 46 for reception in said slit. A second slit 47 is formed in the main body portion 10, and projecting from the cut edge 23 there is a tongue 48 adapted for reception in the slit 47.

The blank A as it is shown in Figure 5, is adapted to be flexed upon the several scored lines from the flat position in which it is shown and in which position it has, except for thickness, two dimensions, that is length and breadth, into a third dimension of depth, thereby providing the display device illustrated in Figures 1 to 4.

To accomplish this flexing of the blank, the area 44 is first bent slightly downward in Figure 5. The two cut edges 20 and 23 are then brought together until the extended portion F passes behind the body portion 10 at the base of the extension H. In this latter position, the tongue 46 may be engaged in the slit 45 and the tongue 48 engaged in the slit 47. The tongue 46 will be of the so-called locking tongue type in order to hold the blank in its flexed position and while the tongue 48 is not shown as of the locking tongue type, it may if desired be so constructed. Its primary function, however, is to retain the two overlapped sections of the body portion in contact with each other.

In flexing the blank as above described, the blank bends or folds upon the several scored lines heretofore mentioned, the area 44 underlying the area 50 between the scored line 32 and the edge 21, while the area 51 between the scored lines 34 and 41, overlies the area 52 bounded by the scored line 33, radially scored line 37 and a portion of the cut edge 20. Folding or bending upon the straight scored line 32, arcuate scored lines 35 and 36 and the radially scored lines 37 and 38 causes the bottom 11 to stand up or assume in cross sectional form, a dihedral angle, while the marginal flange 12, depends or extends downwardly from the upper edge of the main body portion 10.

In flexing of the blank as heretofore described, the stock or material from which the device is formed, is placed under some tension and this tension, together with the shape of the device, produces a high degree of strength which renders the device capable of supporting greater weights, and withstanding far greater strains than any other display devices of this general character with which I am familiar.

It will also be readily apparent that such a device as illustrated in Figures 1 to 5 inclusive, may be shipped flat and readily set up by the ultimate user, since to set the device up, it is only necessary to flex the blank sufficiently to permit of interengagement of the tongues 46 and 48 with their respective slits and after the blank has been once flexed, which may be effected by the manufacturer, it has an inherent tendency to assume the set up position upon bringing the extension F into position underlying the main body portion 10 at the base of the extension H.

In addition to display devices of the type above described, I have found that the invention readily lends itself to the production of highly ornamental elements of display devices, such for example as imitation columns, shrines, and similar structural elements, all of which I have produced in actual practice.

In Figures 6 and 7, I have illustrated one manner in which an ornamental display element has actually been produced by me.

The blank from which such a device is formed is illustrated in Figure 7 and after being shaped to provide the desired contour, the blank is cut along the lines 60 and 61 to provide a removable portion which results in a space X. The blank is scored upon the radial lines 63, 64, 65 and 66, extending radially from the point 67. These scores are formed upon the upper face of the blank as it is shown in Figure 7. The blank is also scored upon the lines 68, 69, 70 and 71 which are continuations respectively of the score lines 63, 64, 65 and 66. The score lines 68 to 71 inclusive are, however, formed upon the under face of the blank as it is shown in Figure 7. The blank is also scored upon the lines 72, 73, 74 and 75. These last mentioned score lines are continuations of the score lines 68 to 71 inclusive and they are formed upon the upper face of the blank as it is shown in Figure 7. The blank is scored upon its under face as it is shown in Figure 7 along the lines 76, 77, 78, 79 and 80, and also upon its upper face, along the lines 81, 82, 83, 84 and 85. In addition to the above scoring, the blank is scored along the line 86, which score line terminates at its inner end at the point 67.

It will be noted that the cut edge 60 terminates at its inner end at the point 67 and if the area 87 be bent upon the scored line 86, and the two leg members 88 and 89 thereon brought together by flexing the blank until the scored line 86 and the cut edge 60 are parallel with each other, the blank will be flexed upon the several scored lines, and will be given depth and will produce a structure which is illustrated in elevation in Figure 6. As illustrated in Figure 6, this structure produces a column or similar structure. Its rear side in said figure is, however, the reverse of what is seen in Figure 6, that is to say, it is recessed or set back, which produces a shrine like appearance and has been effectively used by me for this effect.

Figure 8 discloses a slightly modified form of the invention as illustrated in Figures 6 and 7. In the form illustrated in Figure 8, however, instead of employing angles, I employ curved or arcuate scoring lines connecting the longitudinally extending scoring with the result that curved lines instead of straight angular lines of bend are provided.

The blank employed in connection with the form of the invention illustrated in Figure 8 is of substantially the same form as that employed in Figures 6 and 7, its one salient difference being the curved outer end edge 90. The blank in this form is scored upon its upper face in the position in which it is shown along the line 91. It is also scored upon its under face upon the line 92 and upon its upper face along the line 93, this last mentioned score line terminating at its inner end at the point 94. The blank is also scored along a plurality of lines 95 which extend radially from the point 94 and terminate at the points where they intersect the scored line 92.

If, now, this scored blank be flexed in the same manner as described for the blank illustrated in Figure 7, a device similar in appearance to that shown in Figure 6 will result, except of course the several panels will be defined by curved and straight lines instead of straight and angular lines.

In that form of the invention illustrated in Figures 1 to 11, the device is constructed from a blank of cardboard or similar material, which blank comprises a body portion 100, two wing portions 101 and 102 and a display copy area 103. The body portion 100 is scored or creased longi-

tudinally on the lines designated 104, 105, 106 and 107. The body portion 100 is also doubly creased or scored transversely as indicated at 108 and 109.

In addition to the above scorings or creasings, the wing members 101 and 102 are angularly scored on the lines 110 and 111. These wing members are formed with projections 112 and are scored transversely as at 113 in order that the sections 112 may fold upon their respective wing members.

Each wing member 101 and 102 is provided with two locking tongues 115 and 116 and these locking tongues are adapted to be received in slots 117 in the display copy area 103 to hold the device in its set up position.

In setting up the device the wings 101 and 102 are folded rearwardly upon the two angular scored or creased lines 110 and 111. This throws the wing members upwardly the body portion of the blank bending downwardly upon the scored or creased line 104 upwardly upon the creased line 105 and rearwardly upon the creased line 106, the copy display area 103 being bent forwardly to a vertical position on the scored or creased line 107. After the blank has been folded as described the two locking tongues 115 and 116 will lie in registration with each other and will then be free to be inserted in their respective slots or openings 117. As best illustrated in Figure 10, the sections 112 fold upon the crease or score lines 113 to a position in face to face relation with their respective wings 101 or 102 and behind a portion thereof as indicated at 120 in Figure 10.

This form of the invention provides a display device which has a plurality of stepped supporting shelves or platforms from which extends vertically a relatively large copy display area which device is possessed of considerable strength.

Thus it will be readily apparent that the present invention provides a new and novel method of manipulating cardboard and other flexible materials to produce new and novel effects in display devices and permits the scoring and folding or flexing of materials along curved and irregular lines in a manner which to my knowledge has never before been accomplished.

While in the present presentation of the invention I have shown three forms in which it may be carried out, I do not wish to be limited to these forms illustrated since I have practiced the invention in many other forms too numerous to illustrate and describe herein. Furthermore, I have mentioned only scoring as the means employed to weaken the material or stock to form definite lines of fold or flexing, but I wish to be understood that I may use creasing or other well known methods of forming definite lines of fold in materials of a foldable nature.

Having thus described the invention, what is claimed as new and what it is desired to secure by Letters Patent of the United States, is:—

1. A blank or cardboard circumflexed to produce a re-entrant portion terminating in an apex or reduced portion, a definite line defining and bounding the base of the re-entrant portion, said defining and boundary line comprising a plurality of score lines arranged in end to end in angularly disposed relation, and score lines extending from the junction points of the angularly disposed score lines to the apex or reduced portion of the re-entrant portion.

2. A blank of cardboard circumflexed to provide a re-entrant portion having converging walls, a definite line defining and bounding the base of

- the re-entrant portion, said defining and bounding line comprising a plurality of connected score lines arranged in end to end angular relation, and converging score lines originating at the ends 5 of the angularly disposed score lines which form the defining and boundary line of the re-entrant portion and extending transversely of said re-entrant portion throughout the width thereof.
3. A display device formed from a flat blank of 10 foldable material, said blank comprising a main body portion, a plurality of elongated extensions projecting from the main body portion of the blank, crease or score lines traversing the main body portion of the blank, crease or score lines traversing the extensions of the blank in angular 15 relation to the crease or score lines of the said body portion thereof, the elongated extensions

being secured in a drawn-together position so as to circumflex said blank on said crease and score lines and produce tension in the device.

4. A display device formed from a flat blank 5 of foldable material, said blank comprising a main body portion, a plurality of elongated extensions projecting from the main body portion of the blank, crease or score lines traversing the main body portion of the blank, crease or score lines extending longitudinally of said extensions in continuation of the crease or score lines of the body portion of the blank and in angular relation thereto, the elongated extensions being secured in a drawn-together position so as to circumflex said blank on said crease and score lines and produce 10 tension in the device. 15

RICHARD EATON PAIGE.
